UNITED STATES PATENT OFFICE

154,221

DESIGN FOR A SPECTACLE TEMPLE

Raymond F. E. Stegeman, Greece, N. Y., assignor
to Bausch & Lomb Optical Company, Rochester,
N. Y., a corporation of New York

Application April 16, 1948, Serial No. 145,779

Term of patent 14 years

(Cl. D57--1)

To all whom it may concern:

Be it known that I, Raymond F. E. Stegeman, a citizen of the United States and a resident of the town of Greece, county of Monroe, and State of New York, have invented a new, original, and ornamental Design for a Spectacle Temple, of which the following is a specification, reference being had to the accompanying drawing, forming a part thereof.

Fig. 1 is a side elevational view of a spectacle temple, showing my new design.

Fig. 2 is a top plan view thereof.

Fig. 3 is an enlarged fragmentary view of one end of the temple.

I claim:
The ornamental design for a spectacle temple, as shown.

RAYMOND F. E. STEGEMAN.
